UNITED STATES PATENT OFFICE.

CLEMENT H. GRAEFF, OF LAKWOOD, OHIO, ASSIGNOR TO THE AUTO TOOL & GAUGE COMPANY, OF CLEVELAND, OHIO, A CORPORATION OF OHIO.

HAIR-CLIPPING DEVICE.

Application filed August 16, 1924. Serial No. 732,367.

One form of power driven hairclippers heretofore used embodies a hollow frame having a motor therein with a head having a cutting element which is operatively connected to the motor. Such clippers when once assembled have a definite and permanent relationship between the stationary and movable combs, wherefore the cutting element cannot be adjusted to vary the cutting depth. Accordingly the customary practice is to employ clippers having a relatively close cutting adjustment for part of the hair, then to employ other clippers having a coarser adjustment for other parts of the hair. This necessitates the substitution of an entire unit, thus requiring the barber to maintain individual units for each cutting graduation.

One of the objects of my invention therefore is the provision of a clipper having a detachable head, whereby one motor may function to coact with interchangeable heads. In this connection my invention contemplates the provision of means for enabling heads to be readily separated from the frame in an expeditious manner without effecting the adjustment of the cutting elements.

The preferred means for carrying out my invention will hereinafter be fully set forth in the following description which pertains to the accompanying drawings, while the essential features will be summarized in the claims.

In the drawings, Fig. 1 is a slide elevation of a clipping device embodying my invention; Fig. 2 is a plan view of the separable head shown in connection with the clipper in Fig. 1 and illustrating the operating mechanism therein; Figs. 3 and 4 are sections taken on the correspondingly numbered lines in Fig. 2; Fig. 5 is a perspective view showing the relative arrangement of the head and frame as illustrating one means for providing the separable connection therebetween, and Fig. 6 is a plan view partly in section of the clipper showing the head attached thereto.

I have illustrated my invention in connection with a clipper having a hollow frame 10 which constitutes the handle and houses a motor indicated in general at 11, the armature shaft of which is shown at 12. A switch for controlling the operation of the motor is shown in general at 13, while elec-

trical conductors 14 are illustrated as leading into the switch through the end of the frame. Adjacent the forward end of the frame I have provided a head which carries the usual cutting element together with mechanism for operatively connecting the element to the motor.

The cutting element embodies a relatively stationary comb 15 and a relatively movable comb 16, the latter of which is adapted to be oscillated with reference to the first mentioned comb for effecting the cutting operation. To oscillate the member 16, I have shown a worm 17 rigid with the armature shaft and meshing with a worm wheel 18 which is mounted on an upright shaft 19. The hub of the worm wheel is shown as having a recess for receiving a crank pin 20 which may be rigidly attached to a pitman 21. The free end of the pitman may have a pin 22 rigidly attached thereto and operatively connected to a lever 23. This lever may be pivoted intermediately as at 24 and may have the outer end thereof shaped as at 25, to enter a recess 26 in the comb 16.

The mechanism just described is so coordinated that rotation of the armature shaft rotates the worm wheel, which in turn operates the pitman to effect an oscillating motion of the lever 23, thereby causing the comb 16 to oscillate. The comb is guided during such movement by a tongue 27 which lies in a groove 28 in the stationary comb.

To permit the use of interchangeable cutting elements I provide a separable connection between the head and frame, whereby the head and comb actuating mechanism may be readily removed as a unit from the frame, and another substituted therefor in an expeditious manner.

The preferred form for accomplishing the separable connection is such that the change may be effected merely by a slight angular movement of one member with reference to the cooperating member.

The preferred connection between the head and frame is shown in Fig. 5 wherein the frame has a pair of flexible retaining members 30, which are so mounted that the ends thereof are spaced from the forward face of the frame, so as to receive pins 31, 105 which are mounted on the head. The head also has flanges 32 which engage the sides of the frame so as to assist in maintaining

the head and frame in proper coacting position with relation to each other.

This arrangement of interlocking means provides a quick detachable connection between the head and frame and enables heads having different cutting elements thereon to be interchanged without necessitating the use of set screws and other small connecting members, which require careful manipulation and time to make the desired connection. By employing heads having duplicate locking means, then one frame may be used for a plurality of heads, and substitution of one head for another may be made in a simple and expeditious manner.

To effect an operative connection between the armature shaft and the worm wheel I have shown the worm 17 as being rigidly mounted on the shaft beyond the forward face of the frame. Thus, the worm and worm wheel are automatically brought into operating engagement whenever the head is placed over the end of the frame and is locked thereto. To effect such locking action the head is so placed over the frame that the pins 31 are disposed intermediate the member 30 whereupon the head is rotated with reference to the frame until the pins are forced behind the ends of the member 30. The flexible characteristic of the member 30 functions to retain the pins in locked position.

An advantage of a clipper embodying my invention is the fact that heads having different degrees of cutting adjustment may be interchangeably mounted on the same frame, thus obviating the necessity for an individual motor for each head. A further advantage of my invention is the fact that the heads may be readily removed from the frame in an expeditious manner without necessitating the handling of any part of the clipper which may have loose particles of hair embedded therein.

Having thus described my invention, I claim:

1. In a hair cutting device, the combination with a frame, of spaced flexible members carried thereby, each of said members having a locking shoulder thereon, a head having a cutting element mounted thereon,

said head having means cooperating with the shoulders on said members for locking it to said frame.

2. In a hair clipping device, the combination with a frame, of an electric motor mounted therein, a head, a cutting element carried by the head, mechanism within the head for operatively connecting the element and motor, a pair of flexible members mounted on the forward face of the frame and spaced from the armature shaft of the motor, each of said members having a locking shoulder thereon, a pair of aligned inwardly projecting pins carried by the head, said pins being adapted to engage behind the shoulders on said members for locking the head to the frame.

3. A clipping device comprising in combination a frame member, a cutter carrying member associated therewith and yieldable means including a pair of flat indented spring strips for maintaining said members in adjusted position with reference to each other.

4. In combination, a frame, an electric motor mounted therein, a head having a cutting element and operating mechanism carried thereby, means including a pair of flat spring strips, and coacting pins for detachably clamping the head to the frame, a driving member operated by the motor and projecting beyond the frame, and means for effecting automatic engagement between the member and mechanism when the head is brought into operative relationship with the frame.

5. In combination, a head member, a frame member, a pair of oppositely disposed pins mounted on one of said members, a pair of flat spring strips carried by the other of said members and coacting with the pins for clamping the members together, the frame member having an electric motor therein and the head member having a cutting element carried thereby, said cutting element being operatively connected to the motor when the head is clamped to the frame.

In testimony whereof, I hereunto affix my signature.

CLEMENT H. GRAEFF.
